(57) **CLAIM**

The ornamental design for an adjustable wrench head, as shown and described.

DESCRIPTION

FIG. 1 is a perspective view of an adjustable wrench head showing my new design;

FIG. 2 is a front view thereof;

FIG. 3 is a rear view thereof;

FIG. 4 is a left view thereof;

FIG. 5 is a right view thereof; and,

FIG. 6 is a top view thereof.

The broken lines depict portions of the adjustable wrench head that form no part of the claimed design.
